LIGHTING FIXTURE

Frederic C. Winkler, Lakewood, Ohio, and Gilbert L. Moyer, South Bend, Ind., assignors to Westinghouse Electric & Manufacturing Company, East Pittsburgh, Pa., a corporation of Pennsylvania

Application October 9, 1936, Serial No. 104,814
In Australia June 18, 1936

13 Claims. (Cl. 240—100)

Our invention relates, generally, to lighting fixtures, and, more particularly, to ornamental globes and globe caps for indoor lighting fixtures.

Heretofore, indoor lighting fixtures have been provided with globes, or enclosures for the lamp, having an opening, usually in the bottom position, to permit access to the lamp without removing the globe from its holder. Various kinds of covers or globe caps have been used to close the globe opening, such, for example, as rigid covers attached by means of mechanical fastening devices in the form of screws, clips, etc., and flexible covers which may be temporarily distorted to permit their attachment or removal from the globe. Covers of these kinds have disadvantages which are successfully overcome by the present invention. When mechanical devices or elements such as screws, clips, etc., are used to secure the cover cap in place, they cast unsightly shadows, collect dust and require considerable manual manipulation to secure and remove the cover from the globe. In addition, when fragile material such as glass is used for the globe or cover, or both, considerable care must be used to avoid breakage when manipulating the cover. It has also been found that when flexible covers are used, they become badly discolored and unsightly, and eventually deteriorate to such an extent that they either fall out or become fragile and break when removed from or inserted into the globe, requiring frequent replacement. It is well known that lighting units of this kind must be efficient as well as ornamental and must harmonize with the surroundings in which they are placed. Thus the requirements with respect to the covers is that they be of an ornamental nature, efficient as regards the transmission of the light of sturdy construction and easily removable from the globe without damage to either.

In view of the foregoing, it is the object of our invention, generally stated, to provide a lighting fixture having a globe cover or cap which shall be of simple and efficient construction, ornamental, economical to make and which may be readily secured to and detached from the globe without damage to either.

A more specific object of our invention is to provide a cover or cap for a globe opening which may be removed from or secured to the globe with a minimum amount of effort and manipulation and which is positively secured in position.

Another object of our invention is to provide for removably securing a cap or closure directly to a

globe of fragile material by mechanical means in such manner as not to damage the globe.

A further object of our invention is to provide for removably securing a cover or cap to a globe by means of a mechanical device which shall function as an ornamental agency for the cap.

A still further object of our invention is to provide a glass cover or cap for glass or fragile globes of such nature as to produce an ornamental effect when the globe is illuminated and which has the same general appearance as the globe and maintains its desired contour when it is not illuminated.

Another object of our invention is to provide a glass globe cap which is positively secured in position and readily removable by a simple manipulation of its parts.

In carrying out our invention in what appears to be the preferred manner, we provide a cap or cover of the desired material, shape and coloration which may be placed against the outside of the globe to cover the opening. The cap is secured to the globe by means of a holder adapted to be inserted into the globe through the opening to be covered and having lugs or projections which rest upon the inside portion of the globe surrounding the opening. The cap of glass or other material is secured to the holder in such manner that they are normally urged together to clamp the globe therebetween and so that they may be readily separated a sufficient amount to permit the holder to be readily removed from the globe.

For a more comprehensive understanding of the nature and objects of the invention, reference may now be had to the drawing in which:

Figure 1 is an elevational view partly in section of a lighting fixture embodying the principal features of the invention.

Fig. 2 is a plan view of the supporting holder or spider shown in Fig. 1.

Fig. 3 is an elevational view in section of the spider of Fig. 2.

Fig. 4 is a detailed elevational view partly in section of the globe cap shown in Fig. 1.

Fig. 5 is a similar view of a modification of the globe cap of Fig. 4, and

Fig. 6 is a view showing another modification of the globe cap or cover.

Referring now to Fig. 1 of the drawing, there is shown a lighting unit comprising a globe 10 having a bottom opening 11 to permit access to the lamp 12 which may be supported by a suitable socket (not shown) comprising a part of the globe support or canopy 13. The bottom opening

50 55

11 is of such shape and size as to permit of inserting and removing the lamp without removing the globe.

5 In order to close the opening 11, there is provided a cover 14 of any suitable material such, for example, as glass of the same character as that of the globe and of such shape as to give the globe the desired outward appearance.

10 In this embodiment of the invention, the cover 14 is secured to the globe in such manner that it may be readily removed without injury to the globe or the cover and in such a way that it is positively secured by invisible means which may also function to produce an ornamental effect 15 when the globe is illuminated.

The fastening means for the cover comprises, generally, a holder or spider 15 as shown in Figs. 2 and 3 and an operating device 16 the details of which are shown in Figs. 4 and 5.

20 The holder 15 may be in the form of an ornamental spider as shown or any other desired shape or design may be used. It is provided with a plurality of spaced lugs or tongues 17 which are adapted to rest upon the inside edge of the opening 11 as shown in Fig. 1. About the only requirements of the holder are that it be constructed so that it may be inserted and removed through the opening by tipping it from its normal position to permit the lugs to pass through 30 the opening.

The operating device 16 is so constructed that it normally functions to bias the holder 15 and cover 14 together in order to firmly and positively secure the cover in place and so that the cover 35 and holder may be readily separated the required distance to permit sufficient tipping of the holder to enable its removal from the globe.

40 In this instance, the operating device 16 comprises a plunger 18, which may be secured to the holder by means of threads 19 and nut 21 as in Fig. 4 or by threads alone as in Fig. 5, a knob 22 and spring 23. The plunger 18 is provided with a shoulder or collar 24 and the knob with an internal shoulder 25. The spring 23 is placed upon 45 the plunger between the shoulders 24 and 25 in such manner that it is compressed a sufficient amount to force the cover into engagement with the rim of the opening 11.

50 It is now apparent that the cover and holder, which may be termed a globe cap, may be removed as a unit by grasping the knob and pressing the plunger which compresses the spring 23 and moves the cover and holder apart for a distance sufficient to permit the cap to be tipped in such manner that the holder may be removed through the opening.

55 As shown in Figs. 1 and 3 the lugs 17 on the holder and the contour of the holder may be so formed that the cover 14 is maintained in a definite position and that the pressure exerted upon the rim of the opening by the cover is not excessive. In this instance the lugs 17 have two offset portions 26 and 27 which cooperate with the rim of the opening as shown in Fig. 1 to maintain the cover 14 in a definite position.

60 The holder 15 may be comprised of flexible and resilient material in order that the force exerted by the spring 23 may draw it downwardly into contact or in close proximity to the inside of the cover or it may be curved to substantially the same degree as the cover as shown in Fig. 3 with a slight difference in curvature to cause sufficient springing so that the lugs 17 will exert adequate pressure to hold the cover 14 securely in position.

75 It will be readily understood that the holder 15

may be formed in many different designs in order that the shadow cast thereby upon the cover when the globe is illuminated will produce the desired kind of decoration. The design decoration being produced by the holder makes it possible to design a lighting unit which has a smooth and pleasing appearance and one in which the useful light is not unduly obstructed either by the supporting means for the globe cover or by the cover itself.

10 Referring to Fig. 6 there is shown another form of globe cap wherein provision is made for holding the cover 28 and holder 29 together and for separating them in a different manner.

15 In this embodiment of the invention, the holder 29 is provided with a threaded boss 30 through which the screw 31 extends. The screw 31 is provided with a threaded portion 32 adjacent the head 33 which may be screwed into the threaded boss 30 when the screw is rotated.

20 The screw 31 may be rotated and otherwise manipulated by the ornament or handle 34 which is fixed to the end thereof in any suitable manner.

25 The length of the threaded portion 32 of the screw 31 is such that when the parts are in the position shown the threads are disengaged from the boss 30. In order to bias the holder 29 and cover 28 together to clamp the edges of the globe opening, a spring 35 is placed around the screw between the head 33 and boss 30.

30 The holder 29 and cover 28 may be separated a sufficient distance to permit removal of the holder from the globe by pulling downwardly on the handle 34 to compress the spring 35 and at the same time rotating the handle to cause the threaded portion of the screw to engage the threaded boss. Continued rotation of the handle causes the screw 31 to travel downwardly which lowers the cover 28. The holder 29 is held stationary through the engagement of the lugs or 40 tongues 36 with the edges of the globe opening.

35 In view of the foregoing, it is apparent that the lighting unit as a whole or the globe cap or cover, which may be applied to existing globes using flexible caps, have all of the advantages of similar devices now in use but have none of their disadvantages. They are of simple and rugged construction, efficient and are not subject to 45 breakage under ordinary usage or deterioration.

40 It may be stated, in conclusion, that, while the illustrated example constitutes a practical and perhaps preferred embodiment of our invention, we do not wish to limit ourselves strictly to the exact details herein illustrated, since modifications of the same may be made without departing from the spirit of the invention, as defined in the 50 appended claims.

55 We claim as our invention:

1. A lighting unit comprising a light transmitting globe having an opening therein, a rigid cover for said opening, and means including a spring-biased spider member attached to the cover disposed within the globe for releasably securing the cover to the outside of the globe.

2. A lighting unit comprising a light transmitting globe having an opening therein, a rigid cover for said opening, and a manually-releasable spring-actuated spider element attached to the cover for resiliently and detachably securing the cover to the globe.

3. A lighting unit comprising a light transmitting globe having an opening therein, a glass cover for said opening, and manually-operable means including a separate spider member attached to the cover and a biasing spring there-

for for detachably securing the cover to the globe, said means being disposed to constantly urge the cover against the outside of the globe.

4. A lighting unit comprising a globe having an opening therein disposed below the light surface, a glass cover for the opening, and spring-actuated means attached to the cover for detachably securing the cover to the globe over said opening, said means being disposed to function as an ornamental agency when the globe is illuminated and to be invisible at other times.

5. A lighting unit comprising a globe having an opening therein disposed below the light source, a glass cover for the opening, and a separate spider element disposed within the globe and resiliently secured to the cover for detachably securing the cover to the globe, said means being so constituted as to cast an ornamental shadow upon the cover when the globe is illuminated.

20 6. A lighting unit comprising a light transmitting globe having a bottom opening therein, a cover for said opening, a holder adapted to be placed within the globe through said opening to support the cover, and means including a stem extending through the cover and a spring element for resiliently biasing the holder and cover together to clamp the edges of the globe opening, said stem being disposed when rotated to move and retain the holder and cover in spaced relation.

30 7. In combination a lighting fixture globe having an opening therein, a cover plate for the globe opening, a holder adapted to be placed within the globe to support the cover plate, means including a stem extending through the cover plate and a spring element associated therewith for resiliently biasing the cover plate and holder together, said stem being operable from without the globe to effect a separation of the cover plate and holder a sufficient amount to permit the holder to be inserted into the globe through the opening and removed therefrom.

8. A lighting unit comprising a globe having an opening in the bottom thereof, a rigid cover for the opening, a supporting spider adapted to be placed within the globe to support the cover, a stem secured to the spider and extending through the cover, a knob for the cover having a longitudinal opening through which extends the stem and a compression spring interposed between the knob and stem whereby the spider and cover are constantly urged together to clamp the edges of the globe around the opening.

9. A lighting unit comprising a globe having an opening in the bottom thereof, a rigid cover for the opening, a supporting spider adapted to be placed within the globe to support the cover, and means comprising a knob, a plunger attached to the spider and extending through the cover and knob and a compression spring for detachably securing the cover to the globe, said means being operable from without the globe to separate the spider and cover a sufficient distance to permit its removal from the globe as a unit.

10. A globe cap for covering a globe opening comprising a rigid glass cover member adapted to be supported in contact with the outside of the globe, a holder adapted to be placed within the globe to support the cover member, a stem for the holder extending through the cover member, and a spring on the stem for resiliently securing the holder and cover together, said stem being operable to separate the holder and cover.

11. A detachable cap for a globe opening comprising a rigid glass cover member adapted to be supported in contact with the outside of the globe, a holder adapted to be placed within the globe, a plunger attached to the holder and extending through an opening in the cover member and a spring interposed between the cover member and the exposed end of the plunger for urging the cover member and holder together to clamp the globe around the opening.

12. A detachable cap for a globe opening comprising a rigid glass cover member adapted to be supported in contact with the outside of the globe, a spider adapted to be placed within the globe, and means comprising a stem and a spring associated therewith for resiliently biasing the cover and spider together, said stem being operable from outside the globe to effect a separation of the cover and spider to permit the insertion and removal of the spider from the globe.

13. A lighting unit comprising a globe having a bottom opening, a cover for the opening, a separate spider member adapted to be placed within the globe through said bottom opening to support the cover, and means including a stem interposed between the spider member and cover and a spring member carried by the stem for biasing the spider member and cover together in clamping relation with the edge of the globe opening.
